Fig 7

FIG. 1 is a face view of the numerals zero and double zero showing my new design;

FIG. 2 is a face view of the numerals 10, 20, 30, 40, 50, 60, 70, 80, 90 therein;

FIG. 3 is a face view of the numerals 01, 1, 11, 21, 31, 41, 51, 61, 71, 81, 91 therein;

FIG. 4 is a face view of the numerals 02, 2, 12, 22, 32, 42, 52, 62, 72, 82, 92 therein;

FIG. 5 is a face view of the numerals 03, 3, 13, 23, 33, 43, 53, 63, 73, 83, 93 therein;

FIG. 6 is a face view of the numerals 04, 4, 14, 24, 34, 44, 54, 64, 74, 84, 94 therein;

FIG. 7 is a face view of the numerals 05, 5, 15, 25, 35, 45, 55, 65, 75, 85, 95 therein;

FIG. 8 is a face view of the numerals 06, 6, 16, 26, 36, 46, 56, 66, 76, 86, 96 therein;

FIG. 9 is a face view of the numerals 07, 7, 17, 27, 37, 47, 57, 67, 77, 87, 97 therein;

FIG. 10 is a face view of the numerals 08, 8, 18, 28, 38, 48, 58, 68, 78, 88, 98 therein; and

FIG. 11 is a face view of the numerals 09, 9, 19, 29, 39, 49, 59, 69, 79, 89, 99 therein.

I claim:

The ornamental design for a font of numbers, as shown and described.
